INTERMITTENT TRANSMITTER FOR CARRIER-DESPATCH SYSTEMS.

1,181,584.

Specification of Letters Patent.

Patented May 2, 1916.

Application filed August 18, 1913. Serial No. 785,197.

To all whom it may concern:

Be it known that I, MERTON L. EMERSON, a citizen of the United States, residing at Braintree, in the county of Norfolk and 5 State of Massachusetts, have invented certain new and useful Improvements in Intermittent Transmitters for Carrier-Despatch Systems, of which the following is a specification.

10 This invention relates to despatch systems in general and more particularly to pneumatic despatch apparatus, and has for one of its objects the provision of improved means for transmitting a plurality of carriers from a despatching terminal or station in definite, spaced relationship to each other.

Another object of my invention is to provide an improved despatching terminal or 20 transmitter which shall be positive and automatic in operation and simple in construction.

I further aim to provide a gravity or other type of transmitter for elongated carriers in which the parts thereof are so arranged that carriers will pass into it or out 25 of it at constant predetermined intervals.

These and others objects will be herein-after referred to and the novel elements and combinations of elements whereby they may 30 be attained will be more particularly set forth in the claims appended hereto.

In the accompanying drawing, which forms a part thereof and in which like reference characters designate like parts in the 35 respective views, I have exemplified a preferred construction; but I am aware that various changes and modifications may be made herein without departing from the spirit of my invention, and hence desire to 40 be limited only by the scope of said claims.

In the drawing, Figure 1 is a vertical longitudinal section of a transmitting terminal, in the present instance of the gravity type; the terminal having connected thereto mechanism for intermittently effecting operation 45 thereof. Fig. 2 is a vertical section of a valve which constitutes one of the elements of the said mechanism.

In the preferred construction illustrated 50 the transmitter and associated parts are so

connected that pressure is normally maintained between an inner and an outer gate; which pressure is periodically spilled to allow said gates to operate.

Referring now, to Fig. 1, a transmission 55 tube 1 is therein shown as provided with the usual pressure-fluid supply pipe 2; compressed air normally passing from pipe 2 into pipe 1 through the apertures 3 in the connection 4 between said pipes, as indicated by the adjacent arrow.

The terminal proper, broadly designated 5, is adapted to direct preferably elongated carriers (such as are used for the transmission of mail matter or the like), one of 65 which designated 6 and indicated in dotted lines, is shown in position upon the receiving shelf 7 of said terminal, into the connection 4 for transmission through tube 1. A gate or valve 8, preferably pivotally connected at 9 to an arm 10 which in turn is 70 pivotally mounted at 11 within the upper portion of the terminal, normally closes the aperture leading into said terminal, through which the carrier passes from the shelf 7. 75

The arm 10 is weighted as at 12 so that it together with the gate 8 normally occupy the positions in which these parts are shown in full lines in the figure. If, however, a carrier be in place upon the shelf and the 80 pressure upon opposite sides of the gate 8 be substantially equal, the weight of the carrier will normally be sufficient to open said gate; the carrier thereafter dropping into a chamber 13 in the transmitter by gravity 85 and coming to rest against a second or inner gate 14 which may be identical in construction with the gate 8 just described. For convenience the pivoted arm of this second gate has been designated 10' and the pivotal 90 axis thereof 11'.

Bowl-shaped casings or caps 15 and 15' respectively cover the apertures in the upper and lower extremities of the terminal 5 into which the gates 8 and 14 may be driven by 95 the descending carrier; said caps providing recesses for the reception of the respective gate supporting and closing parts.

A by-pass or conduit 16 is provided around the gate 14 and has therein a valve 100

17 or other suitable means for limiting the flow of air therethrough to a determined amount; or in other words, in effect, valve 17 affords a means for timing said flow of air and thereby the period required for the equalization of pressure in chamber 13 and connection 4, as hereinafter referred to.

In the wall of the chamber 13 is a port 18 which leads into a small chamber 19 within 10 which rides a spill valve 20. When this spill valve is in its lower position, as shown in Fig. 1, communication between the port 18 and a port 21 in the wall of chamber 19 which opens to the outer air, is cut off by 15 said valve; and the latter is normally held in this position through the instrumentality of a spring 22 mounted upon the stem 23 of said valve. A small port or aperture 24 in the upper portion of the casing 25, within 20 which is the chamber 19, maintains the upper end of said chamber at all times in communication with the atmosphere.

Connected to the lower end of the valve casing 25 of valve 20 is a small pipe 26 25 which leads to a valve the casing of which has been designated 27. The construction of this valve and its casing is shown in Fig. 2; the valve proper, 28, being of the plunger type and not dissimilar to the valve 20, previously referred to.

In the present instance the valve 28 is normally maintained in its upper position by a coil spring 29; the upper extremity of which is received in a recess in the valve 35 while the lower extremity of said spring is seated in a corresponding recess in the cap 30 which closes the lower end of the casing 27.

The cap 30 is perforated as at 31 so that 40 the space below valve 28 is at all times in communication with the outer air; and a port 32 near the upper end of the valve casing 27 permits the outer air to freely enter the pipe 26 when valve 28 occupies its upper 45 or normal position; said valve being annularly recessed to provide the necessary communication between port 32 and said pipe. The lower head of valve 28 normally closes a port 33 in the side of valve casing 50 27 and thereby prevents ingress of pressure fluid, *e. g.* compressed air, from a pipe 34 which for present purposes may be regarded as the source of said fluid.

A stem 35 projects upwardly through the 55 top of casing 27 from the valve 28 and carries a friction roller 36 which is adapted for engagement with the peripheral surface of a cam 37. This cam is rotarily mounted upon a shaft 38 which also carries a wheel 60 39, or its equivalent, by means of which said shaft may be driven.

As somewhat diagrammatically indicated in Fig. 1, the wheel 39 is driven by a worm 40 which meshes therewith and which worm

in turn may be driven by an electric 65 motor 41.

The operation of the transmitting mechanism is as follows: The motor 41 is preferably continuously driven and thereby the cam 37 is driven in the direction of the arrow indicated thereupon. This causes a periodic or re-current depression of the valve 28; the latter, of course, rising to its normal position as soon as the shoulder 42 of the cam 37 passes the roller 36; spring 29 75 constantly pressing said roller toward the cam surface. When valve 28 is thus depressed the first portion of its downward movement covers the port 32 in casing 27 and thereafter the port 33 is uncovered; 80 permitting a flow of pressure fluid from pipe 34 into pipe 26 whereby to raise valve 20 against the action of its spring 22. This movement of the latter valve opens chamber 13 to the atmosphere and pressure upon 85 opposite sides of the gate 8 is thereupon equalized. If now the carrier 6 be in position upon the shelf 7 and resting against the gate 8, the weight of the carrier will overcome the counter weight 12 and gate 8 will 90 be swung into the position in which it is shown in dotted lines in Fig. 1; the carrier descending until it rests against gate 14. It may be here noted that the chamber 13 is of sufficient length as compared to the 95 length of the carrier to permit gate 18 to be closed by its weight 12 shortly before the carrier has come to rest against the second or inner gate. In the meantime the rotation of cam 37 has allowed valve 28 to resume the position into which it tends to move, whereupon communication between pipes 34 and 26 is again cut off and the latter pipe is opened to the atmosphere through port 32. Spring 23 thereupon 105 moves valve 20 to its lower position, closing communication between the chamber 13 and the atmosphere, and pressure fluid from the pipe 2 then finds its way more or less slowly through the by-pass 16 until pressure in the 110 chamber 13 equals that within the connection 4, whereupon gate 14 is opened by the weight of the carrier reposing thereagainst and permits said carrier to drop downwardly into the transmission tube 1; gate 14 115 closing immediately thereafter under the action of its counterweight 12'.

Assuming now that a second carrier 6 has meanwhile been placed upon the shelf 7 at the end of a measured interval following 120 the closure of gate 8; it will be evident that a pre-determined time must thereafter elapse before this carrier can enter chamber 13; this time depending upon the speed of rotation of cam 37 which determines the spacing 125 of the time periods during which gate 8 may be opened.

The valve 17 permits of so regulating the

flow of air from the pipe 2 into chamber 13 as to insure the proper closure of gate 14 before the reestablishment of communication between chamber 13 and the outer air; 5 but the conduit or passage-way through which the air under pressure is exhausted from chamber 13 is preferably materially larger than the passage afforded past the valve 17 in the by-pass 16, whereby the pressure fluid in said chamber may be promptly 10 and effectively spilled.

It will thus be seen that by reason of the above described simple construction carriers may be successively despatched from the 15 transmitter with the assurance of a proper and pre-determined spacing therebetween; the desired result being attained positively and the mechanism being such that the likelihood of derangement thereof is reduced 20 substantially to a minimum.

While the transmitter shown is of the gravity type it is obvious, of course, that the principles of the herein described invention may be applied to other types of transmitters. For this reason I have in certain of 25 the appended claims referred to the transmission tube as a means for guiding carriers from the transmitter in a determined direction.

30 In conclusion I particularly direct attention to the automatic establishment, by means of the cyclically acting mechanism employed, of definitely appointed or pre-determined recurrent carrier-despatching periods, during which and at no other time, normally, can elongated carriers be inserted 35 into and despatched from a chamber in the transmitter, said carriers being so guided during their movement into and out of this 40 chamber and in fact in substantially all positions thereof as at all times to definitely locate their longitudinal axes pre-determinedly with respect to the transmission tube. In other words these carriers are not 45 permitted to tumble around with their axes haphazardly located, but no matter how moved with respect to the tube during their progress thereto, each successive carrier as it reaches any given point in its path of 50 travel has its major axis located in the same line that the axis of the preceding carrier occupied when this latter carrier arrived at said point, and the carriers are so held during their passage into the tube as to prevent 55 inadvertent rotational movement of their major axes about their respective centers of gravity.

Having thus described my invention, what I claim is:

60 1. A pneumatic carrier despatch system comprising a carrier despatch tube, an elongated headed carrier for articles to be transmitted, a transmitter having provisions for supporting said carrier in position for des-

patch therethrough, said provisions including a movable element for engaging a head of said carrier and adapted to normally oppose the advance of said carrier, mechanism for permitting said carrier to advance past said element only at pre-determined and automatically recurrent intervals of time, means for automatically establishing a sequence of such intervals and means for establishing a carrier propelling current of air through said tube. 65 70 75

2. A pneumatic carrier despatch system comprising an elongated carrier, a substantially stationary transmitter, means for guiding the advance of a carrier from said transmitter in a determined direction, said 80 transmitter having provisions for supporting said carrier end foremost preparatory to the despatch thereof along said guiding means, continuously driven cyclically acting mechanism for effecting the despatch of said 85 carrier during a pre-determined and limited period of time, and a source of power for continuously driving said cyclically acting mechanism.

3. A pneumatic despatch system comprising a despatch tube, an elongated carrier, a transmitter having provisions for stationarily supporting said carrier successively in two positions and having also means to prevent inadvertent rotation of the major axis 95 of said carrier about the center of gravity of the latter during the movement of said carrier from the first to the second of said positions, cyclically-acting mechanism for controlling the displacement of said carrier 100 from one of said positions, and auxiliary means for controlling, the displacement of said carrier from the other of said positions, said auxiliary means co-acting with said cyclically-acting mechanism in the despatch 105 of said carrier and the periodicity thereof being definitely related to that of the cyclically-acting mechanism.

4. A pneumatic carrier despatch system comprising a despatch tube, a transmitter in alinement with said tube, said transmitter having means for supporting a plurality of carriers to be successively despatched, co-acting means for despatching said carriers through said tube, in spaced relationship, 110 each upon the arrival of a determined instant of time, and means independent of said carriers, for automatically predetermining the times when said carriers may be thus despatched. 115 120

5. A pneumatic carried despatch system comprising a despatch tube, a transmitter in alinement with said tube, having means for supporting a plurality of carriers to be successively despatched and co-acting means for despatching said carriers through said tube 125 in spaced relationship, each upon the arrival of a predetermined instant of time, said in-

stant of time in each case being independent of the emplacement of any preceding carrier in the transmitter.

6. A pneumatic carried despatch system comprising a transmitter, means for guiding the advance of an elongated carrier from said transmitter in a determined direction, said transmitter having means for supporting in axial alinement a plurality of elongated carriers to be successively despatched, and co-acting means for despatching said carriers in spaced relationship each upon the arrival of a predetermined instant of time, said instant of time in each case being independent of the emplacement of any carrier in the transmitter, said co-acting means having provisions for automatically effecting a recurrence of the carrier-despatching period at definitely spaced intervals.

20 7. A pneumatic carrier despatch system comprising a despatch tube, an elongated carrier, a transmitter to positively guide said carrier endwise into said tube and having means for separately and independently supporting a plurality of carriers to be successively despatched, each with its major axis pre-determinedly disposed with respect to said tube and in substantial alinement end to end with the one of said plurality of carriers most nearly adjacent thereto, co-acting means for despatching said carriers in spaced relationship, each upon the arrival of a predetermined instant of time, and means for automatically establishing a sequence of such predetermined instants of time independently of said carriers.

40 8. A pneumatic carrier despatch system comprising a despatch tube, elongated carriers to travel through said tube, a transmitter to guide the advance of each of said carriers therethrough and to hold the major axis of each carrier against inadvertent rotation about the center of gravity of said carrier during the advance of the latter through said transmitter into said tube, and power-driven mechanism to co-act with said transmitter to effect an intermittent step-by-step movement of each carrier through said transmitter toward said tube at cyclically recurrent and pre-determined intervals of time.

50 9. A pneumatic carrier despatch system comprising a tube for the despatch of elongated carriers, a transmitter having means to guide the advance of a carrier endwise toward said tube, mechanism adapted to co-act with said transmitter, to effect an intermittent step-by-step movement of carriers through the latter at cyclically recurrent and predetermined intervals of time, and means for continuously driving said mechanism.

60 10. A pneumatic carrier despatch system comprising a tube for the despatch of elongated carriers, a transmitter having means

to guide the advance of each carrier endwise 65 toward said tube, mechanism to co-act with said transmitter, to effect an intermittent step-by-step endwise movement of carriers through the latter at cyclically recurrent and pre-determined intervals of time, and 70 means to automatically establish a sequence of said intervals greater than two in number.

11. In a pneumatic despatch apparatus, a tube for the transmission of carriers, a transmitter for introducing carriers into said tube 75 having a chamber and two gates one of which controls ingress of a carrier into and one of which controls egress of said carrier from, said chamber, one at least of said gates being normally closed and said chamber being in direct communication with said tube when said normally closed gate is open, automatically recurrently-acting mechanism for opening said normally closed gate to place said chamber in said direct communication with said tube to permit of the passage into said tube of a carrier to be despatched, co-acting means for controlling the other of said gates, and means to prevent inadvertent rotational movement of an axis 80 of said carrier about the center of gravity of the latter so long as said carrier is passing from said last mentioned gate into said tube.

12. In a pneumatic despatch apparatus, a tube for the transmission of carriers, a transmitter for introducing carriers into said tube having a chamber and two gates one of which controls ingress of a carrier into said chamber and one of which controls egress of said carrier from said chamber, said chamber opening into the tube when the gate last aforesaid is open, both of said gates being normally closed, automatically recurrently-acting mechanism for controlling one of said gates, co-acting means for controlling the other of said gates, and means to prevent inadvertent rotational movement of an axis of said carrier about the center of gravity of the latter during the passage of said carrier 105 from the gate which controls its egress from said chamber, into said tube.

13. In a pneumatic despatch apparatus, an elongated carrier, a tube for the transmission of said carrier, a transmitter for introducing said carrier into said tube having a chamber and two gates one of which controls egress of the carrier into said chamber and one of which controls egress of said carrier from said chamber into said tube, said chamber opening into the latter when the gate last aforesaid is open, said gate being normally closed, automatically recurrently-acting mechanism for opening one of said gates to place said chamber in communication with said tube, co-acting timing means for controlling the other of said gates, and means to prevent inadvertent rotational

- movement of the major axis of said elongated carrier about the center of gravity of the latter during the passage of said carrier from the gate which controls its egress from 5 said chamber, into said tube.
14. In a pneumatic despatch apparatus, a tube for the transmission of carriers, a transmitter for introducing carriers into said tube having a chamber and two gates one of 10 which controls ingress of a carrier into, and one of which controls egress of said carrier from, said chamber, means for normally equalizing the pressure in said tube and chamber, and automatically recurrently-acting 15 means for varying the pressure in said chamber from that in said tube at spaced intervals.
15. In a pneumatic despatch apparatus, a tube for the transmission of carriers, a transmitter for introducing carriers into 20 said tube having a chamber and a gate controlling the ingress of a carrier into said chamber, said chamber being normally subjected to a determined pressure, automatically 25 recurrently-acting means for periodically varying the pressure in said chamber from said determined pressure, and pressure controlled means for controlling the egress of a carrier from said chamber.
16. In a pneumatic despatch apparatus, a tube for the transmission of carriers, a transmitter for introducing carriers into 30 said tube having a chamber and a gate controlling the ingress of a carrier into said chamber, said chamber being normally subjected to a determined pressure, automatically 35 recurrently-acting means for periodically varying the pressure in said chamber from said determined pressure, and means 40 for controlling the egress of a carrier from said chamber.
17. In a pneumatic despatch apparatus, a tube for the transmission of carriers, a transmitter for introducing carriers into 45 said tube having a chamber and a gate controlling the egress of a carrier from said chamber, said chamber being normally subjected to a determined pressure, automatically 50 recurrently-acting means for periodically varying the pressure in said chamber from said determined pressure, and means controlled by the pressure in said chamber for controlling the ingress of carriers into said chamber.
18. In a pneumatic despatch apparatus, a tube for the transmission of carriers, a transmitter for introducing carriers into 55 said tube having a chamber and a gate controlling the egress of a carrier from said chamber, said chamber being normally subjected to a determined pressure, automatically 60 recurrently-acting means for periodically varying the pressure in said chamber from said determined pressure, a gate adapt-
- ed to be opened to permit of the ingress of a 65 carrier into said chamber, and means to close said last mentioned gate.
19. In a pneumatic despatch apparatus, a tube for the transmission of carriers, a transmitter for introducing carriers into 70 said tube having a chamber and two normally closed gates which control ingress into and egress from said chamber, a conduit for supplying compressed air to said chamber, a valve for exhausting said compressed air 75 from said chamber, and automatic means, for recurrently actuating said valve at definitely appointed times.
20. In a pneumatic despatch apparatus, a tube for the transmission of carriers, a transmitter for introducing carriers into 80 said tube having a chamber and two normally closed gates which control ingress into and egress from said chamber, a conduit for supplying compressed air to said 85 chamber, a valve for exhausting said compressed air from said chamber, and automatic means, including a cam, for recurrently actuating said valve at definitely appointed times. 90
21. In a pneumatic despatch apparatus, a tube for the transmission of carriers, a transmitter for introducing carriers into said tube having a chamber and two normally closed gates which control ingress into 95 and egress from said chamber, a conduit for supplying compressed air to said chamber, a fluid-pressure actuated valve for exhausting said compressed air from said chamber, and means for periodically varying 100 the fluid pressure which actuates said valve.
22. A pneumatic carrier despatch system comprising a despatch tube, an elongated carrier, a transmitter having provisions for 105 supporting said carrier successively in two positions in each of which the longitudinal axis of said carrier is pre-determinedly located with respect to said tube, cyclically-acting mechanism for controlling the displacement of said carrier endwise from one 110 of said positions, and auxiliary means for controlling the displacement of said carrier endwise from the other of said positions, said auxiliary means co-acting with said 115 cyclically-acting mechanism in the despatch of said carrier and the periodicity thereof being definitely related to that of the cyclically-acting mechanism.
23. A pneumatic carrier despatch system 120 comprising a despatch tube, an elongated carrier, a transmitter having means to stationarily support said carrier successively in two positions and to definitely and positively guide said carrier for endwise travel 125 from the latter of these positions toward and to enter said carrier endwise into said tube, cyclically-acting mechanism for con-

trolling the displacement of said carrier from one of said two positions, and auxiliary means for controlling the displacement of said carrier from the other of said positions, 5 said auxiliary means co-acting with said cyclically-acting mechanism in the despatch of said carrier and the periodicity thereof being definitely related to that of the cyclically-acting mechanism.

15 24. A pneumatic carrier despatch system comprising a tube for the despatch of elongated carriers, a transmitter having means to guide the advance of each carrier endwise

toward said tube, mechanism to co-act with said transmitter, to effect an intermittent 15 step-by-step endwise movement of carriers through the latter at cyclically recurrent and predetermined intervals of time, and means for continuously driving said mechanism.

20

In testimony whereof I have affixed my signature, in the presence of two witnesses.

MERTON L. EMERSON.

Witnesses:

CHARLES O. LAURIN,
ETHEL M. JORDAN.

It is hereby certified that in Letters Patent No. 1,181,584, granted May 2, 1916, upon the application of Merton L. Emerson, of Braintree, Massachusetts, for an improvement in "Intermittent Transmitters for Carrier-Despatch Systems," errors appear in the printed specification requiring correction as follows: Page 3, line 118, claim 4, for the word "predeterminating" read *predetermining*; same page, line 121, claim 5, and page 4, line 4, claim 6, for the word "carried" read *carrier*; same page, line 118, claim 13, for the word "egress" read *ingress*; and that the said Letters Patent should be read with these corrections therein that the same may conform to the record of the case in the Patent Office.

Signed and sealed this 6th day of June, A. D., 1916.

[SEAL.]

J. T. NEWTON,
Acting Commissioner of Patents.
